SHOE TREE

William J. De Witt, Auburn, N. Y., assignor to
 Shoe Form Co., Inc., Auburn, N. Y., a corpora-
 tion of New York

Application February 8, 1934, Serial No. 710,252

14 Claims. (Cl. 12—128.2)

This invention relates to an improvement in a shoe tree by which the walls of a shoe are yieldably held plumped out in substantially the position taken when the shoe is on the foot of the wearer.

The primary object of this invention is to provide a shoe tree having a toe element adapted to enter the toe of a shoe, a heel element adapted to bear against the heel counter of a shoe and an intermediate element connected to both the toe element and the heel element and so constructed and arranged that both toe and heel elements are yieldably separated to the limit determined by the shoe.

15. A further object of this invention is to provide a shoe tree having a toe form, including side walls which may be expanded or contracted and means for yieldably holding the walls expanded against the toe of the shoe.

20. Another object of this invention is to provide a shoe horn having longitudinally extending corrugations therein, such horn being applicable for use in a shoe tree as a heel plate.

Other objects will appear from a consideration 25 of the following description and of the drawing which forms a part thereof and in which

Fig. 1 is a side elevation partially in cross section of a shoe in which a shoe tree, embodying this invention has been placed;

30. Fig. 2 is an enlarged bottom plan view of such shoe tree;

Fig. 3 is a side elevation on an enlarged scale of the intermediate element of the shoe tree;

Fig. 4 is a sectional view, taken along the line 35 4—4 of Fig. 3 of such unit;

Fig. 5 is a perspective view illustrating the use of a shoe horn employed as a heel element for a shoe tree;

40. Fig. 6 is an end view of such shoe horn;

Fig. 7 is a bottom plan view of the toe portion of a shoe tree embodying another form of this invention; and

Fig. 8 is an enlarged cross section thereof taken along the line 8—8 of Fig. 7.

45. The shoe tree illustrated in the drawing comprises a toe element, shown as a toe form 10, an intermediate element, shown as a block unit 20, and a heel element, shown as a heel plate 30, the form 10 and plate 30 being connected to the unit 20 by rods.

The toe form 10 may be of celluloid, metal or other inherently flexible material and comprises side walls 11 which terminate in bottom flanges 12 from which plates 13 and 14 project inwardly.

50. 55. The plates overlie each other and are provided

with pairs of inclined slots 15 and 16 respectively, a portion of each slot 15 registering with a portion of a slot 16. The plates 13 and 14 are secured to the bottom flanges by rivets 17, one plate, here shown as the lower plate 13, by a single rivet and the other plate, in the present instance the upper plate 14, by two rivets. Pins 18 carried by a strap 19 pass through the slots, each pin passing through a slot 15 of one plate and a slot 16 of the other plate. As indicated in Fig. 1 the inclinations of both slots 15 are similar and the same is true of the slots 16, however, the inclinations of the slots 15 are at an angle to those of the slots 16. Hence the advance or retraction of the strap 19 causes the expansion or contraction of the side walls 11.

The unit 20 includes a U-shaped housing 21 having a longitudinally extending groove 22 in each side wall near the top of the housing and a row of holes 23 in each side wall below the groove, such holes being preferably arranged as shown in Fig. 3 so that each row is parallel to the groove above it. In each groove 22 near the rear end thereof is a slot 24. The unit 20 is connected to the toe form by a pair of rods 25 which rest in the grooves 22 and are pivotally secured at one end to the strap 19 here shown as by a loop 26 integral with the strap. The end 27 of one rod 25 is bent at right angles through the slots 24 (see Fig. 2) and is soldered or otherwise secured to the end of the other rod. A spring 28 in the housing attached at one end to the bent end 27 of the rod and at the other end to a tongue 29 yieldably holds the ends of the rods at the forward ends of the slots 24.

35. 40. The heel plate 30 is shown in the form of a shoe horn provided with a strap 31, fixed to the plate below the centre thereof. Rods 32, pivotally secured to the plate 30 by a loop 33 in the strap connect the plate and the unit. As here shown the rods 32 are integrally joined at one end and form the legs of a U-shaped member. Tips 34 at the other ends of the rod, bent at right angles toward each other, are adapted to enter any pair of holes 23 in the unit 20.

45. 50. 55. When the shoe tree is used the toe form 10 is first inserted in the toe of the shoe and the heel plate 30 placed against the heel counter. The pair of holes 23 which receive the tips 34 of the heel plate rods 32 have been so selected that the unit 20 will not easily enter the shoe, a condition permitted by the pivotal connections of the rods 25 and 32 with the toe form and heel plate respectively. Under pressure applied to the unit 20 the unit is forced to take the position shown

in Fig. 1, the spring 28 and slot 24 permitting the rods 25 to move backwards in the grooves 22. The spring however yieldably forces the rods 25 to advance the strap 19 and thereby through the pins 18 and slots 15 and 16 in the plates 13 and 14, to expand the side walls of the toe form until the toe of the shoe has been properly plumped out. The rods 32 are so inclined that the unit is held in the position shown in Fig. 1 and pressure is exerted upon the heel counter of the shoe below the upper edge thereof. It will be noted that the unit 20 and the rods 25 and 32 have a toggle action and that, when the unit 20 is raised above the point at which the toggle 15 is made, the spring 28 acts to advance the rods 25 along the grooves 22. When the toe form is inserted in the shoe the unit 20 is usually grasped so that an expansion of the side walls will take place before the shoe tree reaches its final position in the shoe. The shoe tree may be collapsed by drawing the heel plate out of the shoe, a movement facilitated by the pivotal joiner of the rods 32 to both the plate and the unit.

The end of the heel plate 30 above the strap 25 is here shown longer than the lower end and may, as shown in Fig. 5, be used to facilitate the introduction of the heel into a shoe. This upper end is provided with longitudinally extending corrugations 35. Such corrugations have value 30 for several reasons: First, they stiffen the body of the plate so that thinner material can be used. Second, they permit the shaping of the plate to the shoe. Third, they reduce the amount of friction between the heel of the foot and the body 35 of the horn.

Figs. 7 and 8 disclose the toe portion of a shoe tree which differs in certain respects from that previously described. The toe form 40 which is the toe element of this shoe tree corresponds in 40 construction and material to the toe form 10 and has side walls which terminate in bottom flanges 42. Overlying plates 43 and 44 project inwardly from these flanges and are provided with inclined slots 45 and 46. The plates are secured to the 45 flanges and to each other by rivets 47. It will be noted that the arrangement of rivets shown in Fig. 7 permits a pivotal movement of both the plates. A pin 48 carried by a strap 49 extends through the slots and as the strap is advanced 50 or retracted by means of the rods 55 which are the only part of the intermediate element shown, the side walls of the toe form are expanded or contracted.

The intermediate element of this shoe tree is 55 identical with the corresponding element of the shoe tree first described except as to the forward tips of the rods 55 and hence only the forward ends of the rods are here shown. The strap 49 is attached to the plates as shown particularly 60 in Fig. 8 by the pin 48 so that it is free to swing about such pin as a pivot. Two opposite ends of the strap 49 are bent upwardly to form ears 59 having openings 51 therein which receive the outward ends 52 of the rods 55. The openings 51 65 are arranged in pairs along the ears so that the relation of the rods and strap may be adjusted as desired.

It will be understood that this invention is not 70 limited to the constructions specifically shown and described and that changes may be made in the various elements and other features without departing from the spirit and scope of the invention as set forth in the following claims.

I claim:

75 1. A shoe tree adapted to plump out a shoe

comprising a toe element adapted to enter the toe of the shoe, a heel element adapted to bear against the heel counter of the shoe, an intermediate element and rods pivotally secured to said toe and heel elements and connecting said elements to said intermediate element, the connecting rods pivotally secured to one of the toe or heel elements being pivotally secured to said intermediate element and the connecting rods pivotally secured to the other of said elements being slidably secured to said intermediate element. 10

2. A shoe tree adapted to plump out a shoe comprising a toe element adapted to enter the toe of the shoe, a heel element adapted to bear against the heel counter of the shoe, an intermediate element and rods pivotally secured to said toe and heel elements and connecting said elements to said intermediate element, said toe element being a toe form having expansible and contractible side walls and a strap to which the rods are pivoted and by which the side walls are expanded and contracted as the toe element is inserted into and withdrawn from the toe of the shoe. 15

3. A shoe tree adapted to plump out a shoe 20 comprising a toe element adapted to enter the toe of the shoe, a heel element adapted to bear against the heel counter of the shoe, an intermediate element and rods pivotally secured to said toe and heel elements and connecting said elements to said intermediate element, said toe element being a toe form having expansible and contractible side walls, overlapping plates projecting inwardly from said side walls and having inclined slots in the overlapping portions, and a strap to which the rods are pivoted, said strap including pins which pass through the slots in the plates, whereby the side walls are expanded and contracted as the toe element is inserted into and withdrawn from the toe of the shoe. 35

4. A shoe tree adapted to plump out a shoe 40 comprising a toe element adapted to enter the toe of the shoe, a heel element adapted to bear against the heel counter of the shoe, an intermediate element and rods pivotally secured to said toe and heel elements and connecting said elements to said intermediate element, said intermediate element being a housing having longitudinally extending slots in which the toe element rods slide, and a spring yieldably holding said rods at one end of said slots. 45

5. A shoe tree adapted to plump out a shoe 50 comprising a toe element adapted to enter the toe of the shoe, a heel element adapted to bear against the heel counter of the shoe, an intermediate element and rods pivotally secured to said toe and heel elements and connecting said elements to said intermediate element, said intermediate element being a housing having longitudinally extending slots in which the toe element rods slide and a spring yieldably holding said rods at the forward ends of said slots. 55

6. A shoe tree adapted to plump out a shoe 60 comprising a toe element adapted to enter the toe of the shoe, a heel element adapted to bear against the heel counter of the shoe, an intermediate element and rods pivotally secured to said toe and heel elements and connecting said elements to said intermediate element, said intermediate element being a housing having in its 70 side walls longitudinally extending slots in which the toe element rods slide, and a spring within said housing yieldably holding said rods at the forward ends of said slots.

7. A shoe tree adapted to plump out a shoe 75

comprising a toe element adapted to enter the toe of the shoe, a heel element adapted to bear against the heel counter of the shoe, an intermediate element and rods pivotally secured to said toe and heel elements and connecting said elements to said intermediate element, said intermediate element being a housing having longitudinally extending slots in which the toe element rods slide, a spring yieldably holding said rods at one end of said slots and rows of holes adapted to receive the ends of the heel element rods.

8. A shoe tree adapted to plump out a shoe comprising a toe element adapted to enter the toe of the shoe, a heel element adapted to bear against the heel counter of the shoe, an intermediate element and rods pivotally secured to said toe and heel elements and connecting said elements to said intermediate element, said intermediate element being a housing having in its side walls longitudinally extending slots in which the toe element rods slide, a spring within said housing yieldably holding said rods at the forward ends of said slots, and rows of holes in said side walls parallel to said slots and adapted to receive the ends of the heel element rods.

9. A shoe tree adapted to plump out a shoe comprising a toe element adapted to enter the toe of the shoe, a heel element adapted to bear against the heel counter of the shoe, an intermediate element and rods pivotally secured to said toe and heel elements and connecting said elements to said intermediate element, said intermediate element being a U-shaped housing having in its side walls longitudinally extending grooves in which the toe element rods rest and are free to slide, slots in said grooves at the rearward ends thereof adapted to receive said rods and a spring within said housing yieldably holding the ends of said rods at the forward ends of said slots.

10. A shoe tree adapted to plump out a shoe comprising a toe element adapted to enter the toe of the shoe, a heel element adapted to bear against the heel counter of the shoe, an intermediate element and rods pivotally secured to said toe and heel elements and connecting said elements to said intermediate element, said intermediate element having a U-shaped housing having in its side walls longitudinally extending grooves in which the toe element rods rest and are free to slide, slots in said grooves at the rearward ends thereof adapted to receive said rods, a spring within said housing yieldably holding the ends of said rods at the forward ends of said slots and rows of holes in said side walls parallel to said grooves and adapted to receive the ends of the heel element rods.

11. A shoe tree adapted to plump out a shoe comprising a toe element adapted to enter the

toe of the shoe, a heel element adapted to bear against the heel counter of the shoe, an intermediate element and rods pivotally secured to said toe and heel elements and connecting said elements to said intermediate element, said intermediate element having a U-shaped housing having in its side walls longitudinally extending grooves in which the toe element rods rest and are free to slide, slots in said grooves at the rearward ends thereof adapted to receive 10 said rods, a spring within said housing yieldably holding the ends of said rods at the forward ends of said slots and rows of holes in said side walls parallel to said grooves and adapted to receive the ends of the heel element rods, said 15 rows being below said grooves.

12. A shoe tree adapted to plump out a shoe comprising a toe element adapted to enter the toe of the shoe, a heel element adapted to bear against the heel counter of the shoe, an intermediate element, pivotal connections between said intermediate element and said toe and heel elements, said toe element being a toe form having expandable and contractible side walls which terminate in bottom flanges, slotted plates secured 25 to said flanges, and means in the slots of the plates to which the connection from the intermediate element to the toe element is secured whereby the side walls are expanded and contracted as the toe element is inserted into and 30 withdrawn from the toe of the shoe.

13. A shoe tree adapted to plump out a shoe comprising a toe element adapted to enter the toe of the shoe, a heel element adapted to bear against the heel counter of the shoe, an intermediate element, pivotal connections between said intermediate element and said toe and heel elements, said toe element being a toe form having expandable and contractible side walls, and plates secured to said side walls to which the 40 connection from the intermediate element to the toe element is secured whereby the side walls are expanded and contracted as the toe element is inserted into and withdrawn from the toe of the shoe.

14. A shoe tree adapted to plump out a shoe comprising a toe element adapted to enter the toe of the shoe, a heel element adapted to bear against the heel counter of the shoe, an intermediate element, pivotal connections between said 50 intermediate element and said toe and heel elements, said toe element being a toe form having expandable and contractible side walls, and plates secured to said side walls to which the connection from the intermediate element to the toe element is secured, and said intermediate element including a spring by which the heel and toe elements are normally held a predetermined distance apart.

WILLIAM J. DE WITT. 60
